UNITED STATES PATENT OFFICE.

CHRISTIAN AALBORG, OF WILKINSBURG, PENNSYLVANIA, ASSIGNOR TO WESTINGHOUSE ELECTRIC AND MANUFACTURING COMPANY, A CORPORATION OF PENNSYLVANIA.

TROLLEY.

1,334,943.

Specification of Letters Patent.

Patented Mar. 30, 1920.

Application filed February 19, 1914. Serial No. 819,707.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Trolleys, of which the following is a specification.

My invention relates to current-collecting devices for electric vehicles, and it has special reference to trolleys of the pantograph type which are particularly adapted for high-speed operation and for transmitting relatively large amounts of current from trolley conductors to electric vehicles.

One of the objects of my invention is to provide a device of the above indicated type, that shall be inexpensive, simple and rugged in construction, and adapted for effective and reliable operation and one that shall embody a plurality of pivotally and resiliently mounted contact shoes which are independently and separately supported upon a pantograph frame in such manner that the device shall not be rendered inoperative, even though one of the contact shoes be disabled.

Heretofore, when pantograph trolleys comprising a plurality of pivotally mounted contact shoes have been employed, the shoes have been acted upon by springs which have served in common to perform their intended functions, and, moreover, the shoes have been mounted upon a single pivotal support. In such structures, the shoes may be tilted only with respect to each other and, moreover, because of the common spring support, they are rendered mutually dependent upon each other, and all become inoperative, if one shoe or one spring becomes disabled.

It is to overcome these difficulties that my invention is intended, and, in accordance therewith, I provide a structure in which the several contact shoes are entirely independent, as regards both means of support and operation.

In the accompanying drawing, Figure 1 is a view in side elevation of a portion of a structure constructed in accordance with my invention, and Fig. 2 is a plan view of a portion of the structure shown in Fig. 1, certain parts being removed for the sake of clearness.

Referring to the drawing, the apparatus

here shown comprises a pantograph supporting frame 1, an operating means 2 therefor, a latch 3 for retaining the pantograph in its lowered position, a plurality of pivotal supports or studs 4, 5, 6 and 7 associated with the pantograph frame, a plurality of supporting arms 8, 9, 10 and 11, which are adapted to serve in pairs for pivotally supporting a plurality of contact shoes 14 and 15, a plurality of coil springs 16, 17, 18 and 19 severally disposed around the pivotal supports and adapted to coöperate with the arms hereinbefore mentioned, a plurality of slotted members 21 and 21^a for coöperating with said springs, and flexible conducting strips 34 interposed between the outer sides of shoes 14 and 15 and members of the pantograph frame.

The pantograph supporting frame 1 and the operating mechanism 2 may be of any well known type of construction and pertinent only indirectly to my invention. The frame 1, however, preferably embodies a plurality of rods 22, 23, 24 and 25 which have their upper ends rigidly associated with members or castings 26, 27, 28 and 29. The end castings or members 27 and 28 are of like construction, and each embodies a projecting arm 30 which is adapted to surround a cross rod 31, while each of the end castings 26 and 29 embodies a pair of arms 32 which are spaced apart and adapted to straddle the arms 30 and to surround the cross rod 31. All of the end members 26, 27, 28 and 29 are provided with pairs of upwardly projecting lugs 33 which are adapted to carry the pivotal supports or studs 4, 5, 6 and 7.

Arms 8, 9, 10 and 11 are severally pivotally mounted upon the respective studs 4, 5, 6 and 7, and project in pairs outwardly to pivotally support the contact shoes 14 and 15. The coil springs 16, 17, 18 and 19 severally surround the respective studs 4, 5, 6 and 7 and have free ends bearing upwardly against the under sides of arms 8, 9, 10 and 11 and tending to independently rotate the arms in an upward direction, whereby the shoes 14 and 15 are resiliently pressed against a trolley conductor (not shown) under operating conditions. The pairs of studs 4 and 5, and 6 and 7 are associated with the members 21 and 21^a which are slotted in order to permit of relative horizontal movement be-

tween the studs and serve the purpose of retaining the otherwise free ends of the springs 16, 17, 18 and 19.

The contact shoes 14 and 15 and the latch 5 3 may embody any suitable construction that is familiar to those skilled in the art.

It will be noted that, by reason of the construction shown and described, the several contact shoes 14 and 15 are entirely 10 independent, both with respect to structure and operation.

Modifications may be made which differ materially in point of structural details and arrangement and location of parts without departing from the spirit and scope of my invention, and I desire that only such limitations shall be imposed as are indicated in the appended claims.

I claim as my invention:

20 1. In a pantograph trolley, the combination with a pantograph frame, of a plurality of trolley shoes, and means for yieldingly supporting each of said shoes upon said frame comprising pivot members mounted on said frame, arms pivoted on

25 said pivot members for supporting said shoes, springs exerting an upward pressure on said arms, and links connecting the pivot members of the several shoes, said springs being attached to the links adjacent thereto.

30 2. The combination with a movable pantograph supporting frame, a plurality of pivotal supports associated with the respective halves of said frame and adapted for 35 parallel movement with respect to each other, of a plurality of independently supported members pivotally mounted upon said pivotal supports, springs severally acting upon said members, and a means co-operating with both halves of said frame and engaging said springs.

35 3. A trolley for electric vehicles embodying a pantograph supporting frame, a plurality of pivotal supports associated with the respective halves thereof and adapted for substantially horizontal parallel movement, a plurality of contact shoes mounted upon said pivotal supports, a plurality of coil springs surrounding said pivotal sup-

40 ports and acting upon said shoes, and a plurality of members co-operating with the supports on the respective sides of said pantograph frame and adapted to be engaged by said springs.

45 5. A trolley for electric vehicles comprising a movable pantograph supporting

frame, a plurality of pivotal supports associated with the respective sides thereof, slotted members co-operating with said pivotal supports, a plurality of arms and coil springs associated with said pivotal supports, the springs being adapted to engage said slotted members, and a plurality of contact shoes severally pivotally supported upon pairs of said arms.

60 5. A trolley for electric vehicles embodying a movable pantograph supporting frame, a plurality of pivotal supports mounted on said frame, a plurality of contact shoes mounted upon said supports, a 70 plurality of coil springs surrounding said supports and acting upon said shoes, and link members mounted on said supports and engaging said springs in pairs.

65 6. A trolley for electric vehicles comprising a movable pantograph supporting frame, a plurality of pivotal supports mounted on said frame, a plurality of arms mounted on said pivotal supports, a plurality of link members extending between 80 said supports, a plurality of spring members adapted to engage said arms and said link members, and a plurality of contact shoes pivotally supported upon said arms.

70 7. A pantograph trolley comprising a 85 frame, a plurality of substantially oppositely extending parallel arms pivotally mounted upon said frame, a link extending between the supports for said arms, resilient means engaging said link and tending to 90 raise said arms, and a plurality of current-collecting shoes pivotally mounted upon said arms.

75 8. A trolley for electric vehicles embodying a supporting frame, a plurality of pairs 95 of pivotal supports mounted on said frame, a plurality of relatively movable arms mounted on said supports, a link member extending between the supports of each pair, a plurality of springs mounted on said 100 supports and engaging said link members and adapted to resiliently support said arms, and a plurality of contact shoes severally pivotally mounted upon pairs of said arms.

105 In testimony whereof, I have hereunto subscribed my name this 13th day of Feb., 1914.

CHRISTIAN AALBORG.
